UNITED STATES PATENT OFFICE.

DONALD S. BARROWS, OF ROCHESTER, NEW YORK, ASSIGNOR TO THE T. H. SYMINGTON COMPANY, OF ROCHESTER, NEW YORK, A CORPORATION OF MAINE.

DRAFT-RIGGING.

1,203,259.

Specification of Letters Patent. Patented Feb. 4, 1919.

Application filed June 15, 1917. Serial No. 175,014.

To all whom it may concern:

Be it known that I, DONALD S. BARROWS, a citizen of the United States, residing at Rochester, in the county of Monroe and State of New York, have invented certain new and useful Improvements in Draft-Rigging; and I do hereby declare the following to be a full, clear, and exact description of the invention, such as will enable others skilled in the art to which it appertains to make and use the same.

The invention relates to the art of railway draft rigging and more particularly to that type of draft rigging in which one or more of the movable elements are operatively connected to the car by means of a transversely removable key or keys.

The object of my invention is to provide a fastening means, adapted to be connected to a transversely extending key or keys, to maintain the same in operative position under all conditions of service. To this end, the main feature of the invention, generally stated, comprises a washer or key retaining device, which while simple and inexpensive to manufacture and easy to apply will prevent the accidental displacement of the connecting key or keys.

There are other features of the invention as will be readily apparent from the more detailed description of the single embodiment of the device chosen for the purpose of illustration.

Throughout the specification and drawings like parts are designated by like reference characters.

Figure 1 is a top plan view of a key connected draft rigging showing the key retaining device as applied, and

Fig. 2 is an end elevation of a single key with the key retaining device secured thereto.

The numeral 1 designates the coupler stem, 2 the front follower, 3 the rear follower, 4 the cushioning mechanism interposed between the followers, the type of cushioning mechanism illustrated comprising inner and outer coiled springs designated as 5 and 6 respectively.

The draft sills 7, may be and preferably are formed as Z bars, having their upper flanges 8 turned inwardly and their lower flanges 9 turned outwardly. The numeral 10 designates the tie casting which is rigidly connected to the adjacent faces of the sills 7

in rear of the rear follower 3, and adjacent the ends of the center sills 11, 11. The draft sills 7 are connected at their forward ends to the end sills 12, to the outer face of which is connected the striking casting 13.

To the inner face of each draft sill 7, intermediate the end sill 12 and the tie casting 10 there is connected by means of the rivets 14 a cheek plate 15. Passing through the coupler stem and through aligned slots 65 in the draft links or coupler connecting means 16 and through corresponding slots which may be provided in the cheek plate 15 and which are formed in the sills 7, is the coupler connecting key 17. Corresponding keys 18 and 19 may be provided as shown on the drawings, the forward key 18 being adapted to pass through aligned slots in the front follower 2, the draft links 16, the cheek plates 15 and the draft sills 7. The rear key 19 likewise passes through aligned slots in the rear follower, draft links, cheek plates and draft sills.

Since the means employed to maintain each of the keys in assembled position is identical it will be only necessary for a complete understanding of the device to describe the fastening means as applied to a single key. Adjacent the ends of the key 17 are provided openings 20, the said openings being preferably spaced from the outer faces of the sills 7. The key retaining device or washer preferably comprises a substantially U-shaped member 21, the arms 22 thereof being connected by the curved or rounded portion 23. The arms 22 are spaced apart sufficiently to admit between them the key 17, and are each provided with an opening 24, which when the washer is in position are adapted to register with the opening 20. Through these aligned openings a cotter or other convenient form of fastening means 25 is adapted to extend in order to maintain the washer in position. The arms 22 are of slightly less length than the maximum transverse diameter or width of the key 17, and are approximately twice as wide as the distance between the opening 20 and the adjacent face of the draft sill. The openings 24 are so located with respect to the arms 22 that the forward portion of the arms 22 will contact with the adjacent faces of the center sills should the washer rotate about the axis of the openings 24 as a center and this contact will prevent any rotation of 110

the washer on the cotter or other retaining means 25.

Owing to the increase in weight of cars, and to the increase in the tractive power of 5 locomotives, it has become of prime importance to use a greater number of rivets to connect the cheek-plates to the draft sills than were formerly used. This increase in 10 the number of rivets has, however, caused great difficulty in that it is often impossible 15 to so arrange the rivet heads with reference to the key slots as to prevent the same from being within the path of travel of the usual form of loop washer. To obviate the continual wear which would result from the 20 interference between the loop washer and the rivet heads, it has been customary to either omit the rivets at these points, or to dispense 25 with the washers. Either of these expedients is very detrimental to the draft rigging, 30 since the first renders useless the provision made for additional fastening means, and the second allows the draft key a wide range of lateral movement with the consequent liability by the direct contact with the sills 35 of the cotter of cutting or closing the same, in which event the key is liable to become detached from the car, with disastrous results.

30 The old form of loop washer being loose on the key is often forced by the lateral movement of the key against the legs of the cotter with sufficient force to close the same, and should the cotter become closed it will 35 jar out of place and permit the key to become disengaged.

The foregoing defects are entirely obviated by my invention, since by the use of the improved form of washer, which is of 40 less length than the width of the key, it is possible to so position the washer on the key so that the desired number of rivets may be used without interference between the washer and the rivet heads. This advantage

is aptly illustrated in Fig. 1 of the drawings, 45 attention being directed to the position of the washers on the keys 17 and 19. It will also be noted that the washer 21 is of such width with reference to the cotter pin that when the legs of the cotter are spread, as 50 shown clearly in Fig. 2, in order to retain the cotter in position it will be impossible by lateral movement of the key to bring either leg of the cotter into contact with the adjacent sill, hence all danger of lateral movement 55 of the key closing the cotter is avoided.

Having now fully described the invention, although it will be noted that the terms used are used in their descriptive and not in their limiting sense, what I claim is:

1. The combination with draft sills having aligned slots therein, of a draft rigging involving a coupler, a follower and cushioning mechanism, a key extending through said aligned slots and through one of said draft rigging elements, a washer for said key, said washer comprising a U-shaped member of less length than the width of the said key adapted to straddle one end of said key and means for maintaining said washer 70 in position.

2. In a draft rigging the combination with the draft sills, a coupler, cushioning mechanism, means for operatively connecting the coupler and cushioning mechanism said 75 means including a transversely arranged key, said key being adapted to extend through slots in the said sills, means for retaining said key in position, said means involving a member whose greatest length is 80 less than the maximum transverse diameter of the said key and a fastening means adapted to operatively connect said member and key, the said member being adapted to prevent contact between the fastening means 85 and one of the said sills.

In testimony whereof I affix my signature.
DONALD S. BARROWS.
